UNITED STATES PATENT OFFICE.

ERICK VALDEMAR CARLSON, OF CHICAGO, ILLINOIS.

AUTOMATIC VIOLIN-PLAYER.

1,387,467.

Specification of Letters Patent. Patented Aug. 16, 1921.

Application filed March 6, 1917. Serial No. 152,681.

To all whom it may concern:

Be it known that I, ERICK V. CARLSON, a citizen of the United States, residing at Chicago, in the county of Cook, State of Illinois, 5 have invented certain new and useful Improvements in Automatic Violin-Players; and I do hereby declare the following to be a full, clear, and exact description of the invention, such as will enable others skilled 10 in the art to which it appertains to make and use the same.

This invention relates to mechanically played musical instruments, and has particular reference to automatically played violins.

15 The primary object of the invention is to provide an improved form of bowing or sounding mechanism for operation upon the strings, this mechanism consisting essentially in a single bowing or sounding device 20 which may be operated upon any one of the strings through a selecting mechanism.

A further object of the invention is to provide a pneumatically operated set of devices which will coact with the bowing or 25 sounding element to temporarily associate it in a selective manner with the strings which have been simultaneously fingered by a suitable form of fingering mechanism.

30 A further object of the invention involves the provision of a tremolo action which is pneumatically actuated, and also pneumatically controlled, so that it may be properly brought into operation by the perforated control sheet which also controls the fingering and bowing or sounding devices. In 35 connection with the last mentioned object, it is purposed to provide an intermittent exhaust device for the tremolo pneumatic whereby the bellows is rapidly vibrated and 40 communicates its vibrations to the strings of the instrument.

With the above principal objects in view and such others which relate to the details of construction as will hereinafter appear, 45 my invention will now be fully set forth and described, reference being had to the accompanying drawings.

In the drawings:

Figure 1 is an end view of the upper 50 portion of the instrument showing the sounding devices, the tremolo action, and portions of the motor mechanism,

Fig. 2 is a plan view,

Fig. 3 is a rear view of the sounding 55 mechanism,

Fig. 4 is an enlarged detailed elevation of the sounding mechanism,

Fig. 5 is an enlarged plan view of the tremolo action, and

Fig. 6 is a sectional detail of the tremolo 60 action.

Referring more particularly to the drawings, 1 represents a suitable casing, and frame work upon which is mounted the instrument 2, the latter being a violin of ordinary manufacture, and being elevated from the top of the casing 1, upon suitable standards 3 which do not interfere with the sound producing qualities of the instrument. The casing 1 aside from the instrumentalities 70 which form the subject-matter of this application, carries a suitable fingering mechanism for the strings of the instrument, a pneumatic mechanism for actuating the fingering devices, and a tracker board and 75 music sheet support and mechanism which are, or may be of usual and well known construction, and are therefore not shown or described in the present case. The air motor is located in the upper forward portion of the casing 1, being indicated by the numeral 4 in Fig. 1. The motor bellows is connected by the pitmen 5 to a crank shaft 6, a belt 7 leading from the crank shaft 80 operating the music sheet gearing. Also mounted upon the shaft 6 is a pulley 8 from which a belt 9 extends to a pulley 10 mounted upon a shaft 11. Operating over a second pulley 12 on the shaft 11 is a belt 13 which passes vertically through the top of the 90 casing 1, and operates over a pulley 14 which is mounted upon a longitudinal shaft 15. Said shaft 15 has its bearings in a bracket 16 carried by a standard 16 which rises from the top of the casing 1 adjacent the 95 lower end of the violin and in a second standard 17 which rises at a point opposite or nearly opposite the bridge of the violin. The shaft 15 acts as a drive for a bowing belt 18, which operates over the strings at 100 the proper sounding point, and is stretched between the pulleys 19 and 20. The pulley 19 is carried upon the free end of the shaft 15, while the pulley 20 is mounted upon the free end of a rock arm 21 which is pivoted 105 at 22 upon a bar 23 as shown in Fig. 4. One end of the bar 23 is fixed upon a collar 24 which is set upon the standard 17 near its upper end, and its other end is carried upon a supporting rod 25 which rises from the top 110

of the casing upon the opposite side of the violin body from the standard 17. The bar 23 lies in an inclined position toward the pulley 19, and the arm 21 is inclined in the 5 opposite direction, an upward extension 26 of the latter being connected by a coil spring 27 to a fixed lug 28 carried by the bar 23, so that the belt 18 is properly tensioned against the action of the fingering device as will 10 hereinafter appear.

Also supported upon the top of the casing 1 is a further standard or pillar 29 which rises closely adjacent the standard 25, and carries at its upper end an overhanging arm 15 or bracket 30. Supported by and passing around the arm 30 is an element of a frame 31 which is substantially rectangular in shape, and extends inwardly over the violin body in substantially horizontal position. 20 Carried by the inner arm or side of the frame 31 is a yoke 32 which terminates at one end in the feet 33 which partially support a bearing block 34. The bearing block 34 is also supported by a pair of uprights 35 which depend from the bar 23, so that while 25 the bearing block 34 is freely suspended, it is properly supported against undue vibration and jar. The bearing block 34, as best seen in Figs. 1 and 4 consists of upper and 30 lower plates which have the registering bearing grooves 36 which correspond in number to the number of strings upon the instrument. Within the bearings 36 are supported the rockers 37 which consist essentially of Z-shaped bars or crank-shaped elements supported by their middle elements within the bearing block 34. The inner ends of the rockers are right-angularly turned to provide the fingers 38 which overlie and parallel 35 the strings of the instrument and also project above the lower run of the belt 18, in such position that when the inner ends of the rockers are depressed, they will cause the belt 18 to come into contact with the strings. 40 The fingers 38 are each provided with a shoe 39 of wood, rubber or other suitable material which will not wear unduly upon the belt 18. 45 The opposite ends of the rockers 37 are shaped into transverse bearings to which are 50 pivotally connected the upper ends of the operating rods 40, said rods 40 extending through the top of the casing 1 and having their lower ends adjustably connected to the extensions 41 which project from the plurality of action bellows 42. The pneumatic action bellows 42 are of identical form with the bellows in the pneumatic action of an automatic player piano, and therefore will not be further described at this time, except to 55 point out that the pneumatic tubes 43 extend from the bellows 42 and connect to the usual tracker bar (not shown) over which the perforated control sheet operates, so that when air is admitted through the tracker bar upon 60 registration of an opening of the control

sheet, with the corresponding opening in the tracker bar, the proper bellows 42 is expanded to elevate the rod 40 through whose agency a rocker 37 is operated to cause the bowing or sounding belt 18 to come into contact with one of the strings of the instrument. 70

In connection with the present invention, I provide a tremolo action which operates directly upon the strings, whenever the device 75 is set into operation through the proper registration of a tremolo perforation in the control sheet with a properly positioned opening in the tracker bar through which a connection is made to the pneumatic which controls 80 the tremolo. 44 represents the tremolo pneumatic which is inflated by admission of air through the tube 45, the tube 45 extending to the tracker bar and admitting air to the pneumatic 44 when the tremolo perforation in the music sheet or roll registers with the corresponding opening in the tracker bar. The pneumatic 44 carries the bellows 46 whose movable leaf 47 is connected to a rod or wire 48 by means of the bracket 49. 90 The opposite end of the rod or wire 48 is secured to the rear end of a vibrating lever 50, said lever 50 having a transverse head 51 which engages under the two middle strings of the violin below the bridge thereof and is 95 furthermore provided with a transverse bar 52 which rests upon the outer strings of the instrument, the forward end of the vibrating lever 50 being thus supported wholly by the strings. A weight 53 supported upon the 100 end of an arm 54 which is also secured in the bracket 49 normally presses the movable leaf 47 of the bellows 46 downwardly, and thereby preserves a constant tension on the rod 48 and the lever 50.

Mounted upon the shaft 11 and fixed thereto for constant rotation with the latter is a drum 55 which has bored radially into its periphery a series of ports 56, the ports 56 terminating in longitudinal ports 57 which 110 are extended through and open at the side of the drum. Formed to engage over the periphery of the drum 55 is a shoe block 58 which is normally pressed against the drum in resilient fashion by means of a leaf spring 115 59, the latter carrying the block 58 and having its rear end secured to a bracket 60 suitably mounted upon the frame of the machine. The block 58 has formed therein, a vertical passage 61 which registers successively with the ports 56 as the drum is rotated, and the passage 61, by means of a coupling 62 is secured to the end of a tube 63 which is branched from the tube 45 by means of a T-coupling 64. The result of the foregoing arrangement of parts is this; the drum 55 is constantly rotated with the shaft 11, and therefore maintains a normal succession of the registrations. This, however, does not fully inflate the bellows 46, but only par- 125 130

tially inflates it. When a tremolo perforation in the sheet or roll registers with the tracker bar so that a constant suction is set up through the tube 45 to the pneumatic 44, a constant partial inflation of the bellows 46 is maintained. The additional momentary charges of air afforded by the successive registrations of the ports 56 with the opening 61 in the block 58 create a series of rapid impulses in the inflated bellows 46, which by reason of the constant partial inflation maintained through the tube 45 are communicated to the rod 48 and consequently to the lever 50. These impulses or vibrations are communicated to the strings through the head 51 and the transverse bar 52 in an obvious manner so that a perfect tremolo action is imparted to the strings of the instrument.

20 In the sounding of the strings, the action of the mechanism upon the instrument is as follows; the belt 18 is constantly driven from the motor mechanism through the belts 9 and 13 and the shafts 11 and 15. 25 As a perforated music sheet or roll passes over the tracker bar and the sound producing perforations register with the corresponding openings in the tracker bar, the proper bellows 42 are successively collapsed, 30 so as to throw the rods 40 upwardly. This action rocks the rock elements 37 and throws the fingers 39 downwardly upon the lower run of the belt 18, with the result that the latter is bowed downwardly into contact 35 with the string or strings to be sounded, the belt being allowed to flex through the yieldable mounting of the roller 20. The spring 27 is so tensioned that it quickly lifts the belt out of contact with the strings, 40 when the rock devices 37 are released, but does not interfere with the proper contacting of the fingers 39 with the strings under the action of the rock devices.

The action of the tremolo mechanism has 45 already been pointed out, but it should be noted that by reason of the independence of the bowing or sounding mechanism and the tremolo action, both as to their actuating mechanism and their control, the tremolo fingering may be brought into a piece 50 of music at will and with perfect effect. The constant movement of a single driving belt over the strings and the provision of the pneumatic operated manipulating fingers 55 for slidably pressing the belt into contact with the several strings reduces to a minimum the actuating mechanism which must be driven by the motor.

What I claim as my invention is:—

60 1. An automatic violin player comprising an instrument holding element, a constantly moving endless belt, one of the runs of the belt positioned to overlie the strings of a violin, a plurality of fingers overlying said 65 run, a finger being associated with each

string, and means for individually actuating the fingers to move the belt into contact with the strings.

2. An automatic violin player comprising an instrument holding element, a constantly moving endless belt, means for supporting said belt with one run positioned to extend transversely above the strings of a violin, one end of said run being yieldably mounted, individual fingers for moving the belt into contact with the several strings, and selective means for actuating said fingers.

3. An automatic violin player comprising an instrument holding element, an endless belt, a fixed support and a movable support 80 for said belt, one run of the belt extending to operate transversely across the strings of a violin, and means for selectively moving the belt run into contact with the several strings.

4. An automatic violin player comprising an instrument holding element, an endless belt, a fixed support and a movable support for said belt, one run of the belt extending to operate transversely across the strings of 90 a violin, and a bank of devices for selectively moving portions of the belt run into contact with the strings.

5. An automatic violin player comprising an instrument holding element, a lever having one end extending for close association with all of the strings of a violin, and means operative upon the opposite end of the lever to vibrate the latter whereby a tremolo action is imparted to the strings.

6. An automatic violin player comprising an instrument holding element, a lever having lateral extensions at one end for engagement with the strings of a violin, and means operative upon the opposite end of the lever 105 for vibrating the strings.

7. An automatic violin player comprising an instrument holding element, a lever having one end extended for engagement with all of the strings of a violin, a pneumatic 110 including a bellows and a box, means connecting said bellows with said lever, means for admitting air to the box of the pneumatic, and additional means for introducing rapid intermittent charges of air into the 115 box to cause a vibration of said bellows and lever.

8. An automatic violin player, comprising an instrument holding element, a lever extended for engagement with the strings of a violin, a pneumatic including a bellows and a box, means connecting the bellows with the lever, an air conduit leading to the bellows for admitting air to the box, a branch conduit leading from the first named conduit, a 120 rotary drum having a plurality of peripheral ports, a block operative upon the periphery of the drum and having a port for connecting said branch conduit with the ports and the drum, said drum in its rota- 125 130

tion intermittently providing an additional connection between the atmosphere and the bellows.

9. An automatic violin player comprising an instrument holding element, a lever extended for engagement with the strings of the violin, a pneumatic including a box and a bellows, means connecting the bellows with the lever, an air conduit leading to the box for admitting a partial expanding charge of air to the latter, a branch conduit leading from the first named conduit, a rotary drum having a plurality of peripheral ports open to the atmosphere inwardly of the periphery of the drum, a block operative upon the periphery of the drum and having a port for connecting said branch duct with the ports of the drum, means resiliently forcing the block into contact with the periphery of the drum, said drum in its rotation intermittently providing an additional connection between the atmosphere and the bellows.

10. An automatic violin player comprising an instrument holding element, a constantly rotatable endless belt, one of the runs of the belt positioned to pass transversely above the strings of a violin in spaced relation thereto, a fixed pulley carrying one end of the belt and a resiliently-mounted pulley carrying the opposite end of the belt, a plurality of fingers projecting above the run of the belt, a finger being superimposed over each string, rock levers carrying said fingers, a corresponding plurality of pneumatic ac-

tions, means connecting the pneumatic actions with the rock levers, and means for selectively actuating the pneumatic actions to cause the fingers to press the belt into contact with the strings.

11. The combination with a violin, of a frame work extending transversely across the violin and including a bridge piece, a fixed pulley carried by the frame work, an oscillatory pulley suspended from the bridge piece, a spring also connected to the bridge piece for normally throwing the oscillatory pulley away from the fixed pulley, an endless bowing belt carried over the pulleys, the lower run of the belt lying in closely spaced relation to the strings of the violin, means for constantly driving the belt, a plurality of fingers corresponding in number to the strings extending above the lower run of the belt, and each overlying a string, a plurality of rock levers carried by the frame work and each supporting a finger, and pneumatic actions for selectively rocking the levers to carry the fingers downwardly against the belt, said fingers in contacting the belt carrying the contacted portion into contact with the corresponding string.

In testimony whereof, I affix my signature in the presence of two witnesses.

ERICK VALDEMAR CARLSON.
